UNITED STATES PATENT OFFICE.

HERMAN M. HOELSCHER, OF CHICAGO, ILLINOIS.

FOLDING OR COLLAPSIBLE TOP FOR AUTOMOBILES.

No. 926,118.

Specification of Letters Patent.

Patented June 29, 1908.

Application filed November 5, 1908. Serial No. 461,134.

To all whom it may concern:

Be it known that I, HERMAN M. HOELSCHER, a citizen of the United States, residing in Chicago, in the county of Cook and State of Illinois, have invented a new and useful Improvement in Folding or Collapsible Tops for Automobiles, of which the following is a specification.

My invention relates to folding or collapsible tops for automobiles.

Heretofore in automobiles having bodies furnished with folding or collapsible tops, the openings above the side doors and between the upright collapsible frame members or rods have usually been closed by removable curtains secured on the outside of the top by buttons or other suitable fasteners. Such curtains, when removed, do not interfere with the collapsing of the top, but they are inconvenient and difficult to remove and apply and require considerable time, and their removal or application can ordinarily only be made from the outside or by the chauffeur, although it is frequently very necessary or desirable, especially in cases of emergency, that the occupants of the vehicle should be able themselves to quickly remove such curtains and get out.

The object of my invention is to provide a collapsible or folding top automobile body of an improved construction, wherein the side curtains over the doors will not interfere with the collapsing or folding of the top, may always be in position ready for use, may be readily opened and closed either by the occupants of the vehicle from the inside or by the chauffeur from the outside, and this very readily and quickly, and which will also be of a simple, efficient, neat and durable construction.

My invention consists in the means I employ to practically accomplish this object or result. That is to say, it consists in connection with an automobile body having folding or collapsible top and the customary side doors and openings above the doors between the upright frame members or rods of the top, of removable curtain rods detachably secured within the collapsible or folding top, and preferably to the upright frame members or rods thereof, so that when the curtain rods are removed, the top may properly fold or collapse, and sliding curtains mounted on such rods so that they may be drawn together against the upright frame members

of the collapsible top and thus clear the spaces above the side doors.

It further consists, in connection with these parts, of cords and pulleys for operating the sliding curtains by the chauffeur from the outside.

It further consists in the novel construction of parts and devices and in the novel combinations of parts and devices herein shown and described and more particularly specified in the claims.

In the accompanying drawing forming a part of this specification, Figure 1 is a perspective view of a folding or collapsible top automobile embodying my invention, showing one of the sliding curtains extended or closed, and the other contracted or opened. Fig. 2 is a detail sectional elevation. Fig. 3 is a detail horizontal section on line 3—3 of Fig. 2. Fig. 4 is a detail cross section on line 4—4 of Fig. 2. Fig. 5 is a detail perspective view of the removable curtain rod.

In the drawing, A represents an automobile of any suitable kind or construction having a body B with customary side doors C and folding or collapsible top D, having a cover d of leather or other flexible material and folding frame members or rods d¹ d² and with side openings D¹ between the upright folding frame members or rods d² d².

The side openings D¹ above the side doors C are closed by sliding curtains E of leather or other flexible material, supported upon removable curtain rods F by suitable rings or hangers f, passing through eyelets E¹ in the curtains E. The removable curtain rods F may be detachably secured to the folding or collapsible top of the automobile body by any suitable means. I, however, prefer to employ for this purpose screw studs f¹ and screw thimbles f², the screw studs f¹ having base plates f³ secured to the upright frame members or rods d² of the folding or collapsible top by screws f⁴ so that the curtain rods F may be easily and quickly removed so as to enable the collapsible top D to be contracted or folded when it is desired to use the vehicle as an open one. The removable curtain rods F extend between and are removably mounted upon the front and rear uprights d² d² of the collapsible top and are directly over the side doors C which are between the front and rear seats of the automobile body; and the sliding curtains E may be opened or collapsed either by the

occupants of the rear seat or by the chauffeur or occupants of the front seat as occasion or emergency may require. The flexible sliding curtains E when extended or closed are 5 securely held in this position by elastic holders G having hooks g engaging rings or eyelets E^2 in the curtain and fasteners g^1 secured to the collapsible top D or body B of the automobile. The side members d^3 of 10 the collapsible top D have forwardly projecting extensions d^4 over which the rear edges E^3 of the curtains E overlap so as to produce a tight closure against wind or rain.

To hold the lower edges of the curtains E 15 in their extended or closed position, the same are furnished with large hooks G^1 which engage the side portion b of the automobile body. When the curtains E are contracted or open, they are held in this position by flexible straps G^2 . To enable the 20 sliding and contractible curtains E to be readily opened or closed from the outside or by the chauffeur, I provide the same with cords H extending over pulleys h, said cords 25 extending into easy reach from the chauffeur's seat over pulleys h^1 h^1 , one near the front edge of the side door opening and the other near the rear edge thereof. The cords H H^1 are both attached to the rear edge of the curtain. The chauffeur by pulling on the cord 30 H collapses the curtain by pulling its rear edge directly forward. The occupant by pulling on the cord H^1 which extends first around the front pulley h^1 and then over the 35 rear pulley h^1 also collapses the curtain by pulling its rear edge forward. Further cords H^1 extend to the occupant's seat.

My invention may be applied to automobile bodies with collapsible tops whether the 40 whole top thereof be made collapsible on only a portion thereof collapsible, and whether the top is made collapsible by folding it or by otherwise collapsing or contracting it. For convenience, I have illustrated

my invention as applied to an automobile 45 body, the whole top of which is collapsible by a folding movement.

I claim:—

1. In an automobile the combination of a body, a collapsible top extending over the 50 said body and having front and rear uprights connecting it with the body, the said uprights being collapsible with the top, the body being provided with a side door opening between the said uprights and extending 55 to the bottom of the body, a hinged door fitting the said opening, a detachable rod extending over the said hinged door and carried by the said uprights, and a flexible curtain sliding on the said rod, closing the 60 space between the said uprights and lapping past the top edge of the door, whereby by the sliding of the curtain and the swinging of the door a free exit space may be provided extending to the bottom of the body. 65

2. In an automobile, the combination of a body having front and rear seats, a collapsible top extending over the said front and rear seats and having front and rear uprights connecting it with the body, the body being provided with a side door opening between the said seats, a hinged door fitting said opening, a detachable rod extending over the said hinged door and carried by the 70 said uprights, a flexible curtain sliding on the said rod, closing the space between the front and rear seats and lapping past the top edge of the door and the pull cord extending from the sliding curtain to the said front seat, whereby by the sliding of the curtain and the swinging of the door a free exit 75 space may be provided extending to the bottom of the body. 80
